UNITED STATES PATENT OFFICE.

GEORGE COUSINS, OF OSWEGO, NEW YORK.

MICROMETER CALIPERS.

1,405,295.

Specification of Letters Patent. Patented Jan. 31, 1922.

Application filed April 26, 1920. Serial No. 376,742.

To all whom it may concern:

Be it known that I, GEORGE COUSINS, a citizen of the United States, and a resident of Oswego, in the county of Oswego and 5 State of New York, have invented certain new and useful Improvements in Micrometer Calipers, of which the following is a specification.

My present invention relates generally to 10 micrometer calipers and more particularly to micrometer calipers of the type described and claimed in my co-pending application Serial No. 343,738, filed December 19, 1919, and in connection with which application it 15 is the object of my present invention to provide certain improvements relating in part to the adjustment or relocation of the caliper legs especially in instances of work requiring change of position with celerity 20 and precision, as well as in part to avoidance of breakage in the hands of unskilled persons and also in part to the provision for more minute measurements.

In the accompanying drawings which 25 illustrate my present invention and form a part of this specification,

Figure 1 is a front elevation showing my improvements complete,

Figure 2 is a detail side view of the pod- 30 ger removed,

Figure 3 is a detail longitudinal section through the adjusting screw and the adja- 35 cent end of the adjusting leg,

Figure 4 is a detail vertical section taken 40 on line 4-4 of Figure 1,

Figure 5 is a side view of the device com- 45 plete with the adjusting leg clamped,

Figure 6 is a side view partly broken away 50 and in section showing the adjusting leg re- leased for adjusting movement,

Figure 7 is a side view looking at the op- 55 posite side with respect to Figures 5 and 6.

Figure 8 is a side view of a modified form, 60 and

Figures 9 and 10 are end views, looking 65 at the opposite ends of Figure 8.

Referring now to Figures 1 to 7 inclusive 70 the caliper bar 10 of my improved device is received within the tubular inner ends 11 and 12 of the two caliper legs 13 and 14, the former of which is a stationary leg, though removable from the bar 10, and the latter of which is the adjustable leg.

At one side, and extending somewhat less 75 than half of its circumference, the bar 10 has a toothed surface 15, its teeth being

either in the nature of threads or a rack, for cooperation with the similarly shaped inner surface of one side 16 of each of the lengthwise split leg ends 11 and 12, the op- 60 posite sides of which have inner V-shaped recesses 17 which cooperate with the similarly beveled side face of the bar 10 dia- metrically opposite its toothed surface 15, as plainly seen in Figures 5, 6 and 7. It will 65 be understood that the bar 10 has its toothed surface and beveled faces extending for its full length and providing for similar en- gagement therewith by both of the caliper legs 13 and 14, the inner split bearing por- 70 tions of which have ears 18 in connection with which clamping screws 19 and 20 op- erate. The screw 19 of leg 13, as best seen in Figure 7, has a shoulder abutting one side portion and threads screwing into the other 75 side portion and is manipulated by a knob 21 whose shank may have a diametrical opening 22 for which the podger 23 of Figure 2 is provided. This podger has a handle 24 and a threaded portion 25 and is 80 normally housed in an axial bore of the bar 10 at one end, within a counter-bore of which the threads 25 engage to hold the podger between its periods of use.

The screw 20 of the leg 14 as seen in 85 Figures 5 and 6 has threads screwing into one of the ears 18 and has a knob 26 and an apertured shank 27, the latter of which is provided with a collar 28 rotatable in a re- 90 cess of a supplemental piece 29 attached to the other ear so that the two sides will be spread or contracted in order to quickly free the leg 14 for adjustment lengthwise along the bar 10.

It is obvious that the two legs being thus 95 similarly secured, can in use be quickly and accurately brought into the desired relation, the toothed surface 15 of the bar providing for their relocation at the desired distance while the inclined or beveled faces and the 100 cooperating V-shaped recesses 17 will instantly bring the legs into the same plane when the adjustable leg is clamped by the screw 20.

The outer ends of the legs 13 and 14 105 have split tubular portions 30 and 31, the former being internally threaded for the reception of an adjustable anvil 32 which may have the various shapes shown in full and dotted lines in Figure 1 for different 110 uses in connection with plain surfaces, open- ings, and threads, the said split tubular ends

30 having ears 33 by which it is normally clamped through the use of the clamping screw 34 like the screw 19.

The split tubular end 30 of the adjustable leg 14 is internally threaded to receive an adjustable screw 35, and is cut away at one side to form an opening through which the intermediate plain cylindrical portion 36 of the adjustable screw is exposed to sight 5 with its vertical and longitudinal lines calibrated to cooperate with the calibrations along the upper and lower edges of this recess or cut away portion 37 of the tubular end 31.

15 As seen particularly in Figures 1 and 4 the tubular end 31 has ears 38 by means of which the adjustable screw 35 is clamped by a clamping screw 39 like the screws 19 and 34, and as seen particularly in Figure 20 3 the adjustable screw 35 is provided with an enlarged bore 40 extending therein from one end to receive a spring 41 compressed by means of a screw plug 42 threaded into the outer end of the bore, against the inner 25 head 43 of a feeling pin 44, the latter of which extends from the head 43 through an axial opening of the adjustable screw and projects to a point beyond one end of the same so as to come in contact with the 30 work. By means of this arrangement careless application of the tool to work of greater diameter than that to which the tool is set, which frequently happens in the course of its use in unskilled hands, I provide 35 against disastrous consequences in so far as breaking or straining the caliper legs is concerned by virtue of the yielding qualities of the feeling pin 44 against the tension of spring 41 which serves to normally 40 hold it in the proper position. For example, an amateur mechanic frequently attempts to caliper work revolving in a lathe, something which can be done with the ordinary spring calipers. With the usual rigid 45 micrometer caliper however, the work, if a trifle larger than the caliper space, will seize the caliper and very often crack or break the same in its rotation with the work. The 50 feeling pin I propose avoids such a seizure on account of its yielding capabilities.

The bar 10 is of course to be calibrated so that the measurement is read partially therefrom and partially from the calibrations of the tubular end 31 of adjustable leg 14 55 in respect to the vertical and longitudinal lines of the adjustable screw 35 and, in case further and more minute measurement is desirable or necessary, I provide for the same by means of a centrally apertured disk 60 45 clamped between the outer headed portion of the screw plug 42 and the adjacent end of the adjustable screw 35, the screw plug passing through a central opening in the disk which latter is calibrated around 65 its edge as clearly seen in Figure 5. With

this disk a pointer in the nature of an arm 46 cooperates, one end of this arm being pivotally connected by a screw 47 to the adjustable leg 14 intermediate the ends of the latter so that it may be swung outwardly 70 to the effective position shown in full lines in Figure 1 for cooperation with the disk 45, or inwardly lengthwise of the adjustable leg 14 in order that it may be protected while it is not in use. To cooperate with the screw 47, the podger 23 may terminate 75 in a screw driver end 48.

It is obvious that the measuring ends or work engaging ends of the anvil 32 and adjusting screw 35 may be variously shaped 80 as usual dependent upon the particular work to be calipered, and it is obvious that both of the legs 13 and 14 may be reversed so as to caliper openings, or the anvil 32 and adjustable screw 35 reversed at their outer ends for this purpose. It is obvious furthermore that if the caliper legs are reversed, the bar 10 with its particular shape as described will continue to cooperate with the bar engaging ends of the legs for the purpose of insuring accurate positions of the legs at all times.

In Figures 8, 9 and 10, I have shown a modified construction wherein an adjustable anvil 50 works through, and is clamped within, one split tubular end or leg 51 of a solid rigid U-frame 52, in a manner similar to that in which the bar 10 is held in connection with the adjustable leg 14 in the first form. The opposite end or leg of the frame 52 is of tubular form at 53 and is split and apertured to receive an adjustable screw 54 like the formerly described adjustable screw 35, provided with a calipered disk 55 which in this instance cooperates 95 with an indicating arm 56 pivoted upon the frame 52. This modification illustrates plainly the adaptability of the invention in certain respects to a micrometer caliper of the usual form.

I have also shown in Figure 1 dotted lines indicating a stand or holder engageable with the caliper bar when the latter is used as a bench caliper.

110 I claim:

1. A micrometer caliper comprising a bar, a pair of caliper legs having gaging means at their outer ends and having split tubular inner ends, and clamping screws for the split tubular ends on the bar, said bar having a 115 toothed surface extending partially therearound and lengthwise thereof and having an angular surface extending therealong opposite the toothed portion, and said tubular portions of said legs having their sides 120 formed to cooperate with the toothed and beveled portions of the bar whereby to insure co-planar positions of the legs in fixed spaced relation.

2. A micrometer caliper comprising a bar 130

having a transversely toothed longitudinal surface at one side and a lengthwise extending angular face opposite the toothed surface, and caliper legs having gaging means 5 at their outer ends and having split tubular inner ends embracing the bar and provided with clamping means, the opposite side portions of said tubular ends being internally formed to cooperate with the toothed surface 10 of the bar and its beveled face whereby to insure fixedly spaced and co-planar positions of the legs when clamped to the bar.

3. A micrometer caliper comprising a bar having a longitudinal face at one side of its 15 axis provided with transverse teeth and having beveled faces at the relatively opposite side of its axis and extending lengthwise therealong, and caliper legs having gaging means at their outer ends and having split tubular inner ends embracing the bar and provided with clamping means, one side portion 20 of each of the said tubular ends being toothed to cooperate with the toothed surface of the bar and the other side portion of each tubular end having a recess with flat 25 walls to cooperate with the beveled faces of the bar, as and for the purpose set forth.

4. A micrometer caliper including a bar, a leg adjustable on the bar, an anvil, and an 30 adjustable screw carried by the leg and opposing the anvil, and a spring controlled feeling pin carried by the adjustable screw and projecting beyond the inner end of said screw.

35 5. A micrometer caliper including a bar, a leg adjustable on the bar, an anvil, and an adjustable screw carried by the leg and opposing the anvil, said adjustable screw

having a bore extending inwardly from one end and an axial opening projecting through 40 its opposite end and in communication with the bore, a feeling pin extending through the said opening and having a head in the bore, and a spring compressed in the bore and engaging the head to hold the feeling 45 pin in proper position.

6. A micrometer caliper including a bar, a leg adjustable on the bar, an anvil, and an adjustable screw carried by the leg and opposing the anvil, said adjustable screw 50 having a bore extending inwardly from one end and an axial opening projecting through its opposite end and in communication with the bore, a feeling pin extending through the said opening and having a head in the 55 bore, a screw plug threaded into the outer end of the bore, and a spring in the bore compressed between the said plug and the head of the feeling pin.

7. A micrometer caliper comprising a 60 frame including a pair of caliper legs, an anvil supported by one of the legs, an adjustable screw carried by the other leg and opposing the anvil, a measuring disk fixed to one end of the said adjustable screw, and 65 a pointer carried by the respective leg and cooperating with the said measuring disk, said pointer being in the nature of an arm pivotally connected to the leg intermediate the ends of the latter and movable between 70 positions parallel with and at right angles to the said leg, as described.
